CLAIM

The ornamental design for a carrying case, as shown.

DESCRIPTION

FIG. 1 is a top plan view of a carrying case showing my new design;

FIG. 2 is a side elevational view;

FIG. 3 is an end elevational view taken from the left of FIG. 2;

FIG. 4 is an end elevational view taken from the right of FIG. 2; and

FIG. 5 is a bottom plan view thereof.

The side of the carrying case not shown is a mirror image of the side shown in FIG. 2.

Fig. 1.

Fig. 3.

Fig. 2.

Fig. 4.

Fig. 5.
